UNITED STATES PATENT OFFICE.

JULIUS BRENZINGER, OF NEW YORK, N. Y., ASSIGNOR TO THE MAXAMS
MACHINE CO., OF NEW YORK, N. Y., A CORPORATION OF NEW YORK.

CAN-HEADING MACHINE.

No. 813,482.

Specification of Letters Patent.

Patented Feb. 27, 1906.

Application filed June 16, 1904. Serial No. 212,764.

To all whom it may concern:

Be it known that I, JULIUS BRENZINGER, a citizen of the United States, residing at New York city, Manhattan, county and State of New York, have invented new and useful Improvements in Can-Heading Machines, of which the following is a specification.

This invention relates to a machine for forming the seam or joint between a can-body and the superposed can head or bottom.

The machine may be readily adjusted to different sizes of cans, is easily tended, and operates with rapidity and precision.

In the accompanying drawings, Figure 1 is a front elevation of my improved can-heading machine; Fig. 2, a right-hand end view thereof; Fig. 3, a rear view of the principal parts of the machine; Fig. 4, a detail of the platform and gage-operating mechanism; Fig. 5, a detail of the table-adjusting mechanism; Fig. 6, a horizontal section on line 6-6, Fig. 2; Fig. 7, a vertical section through the table and platforms; Fig. 8, a vertical section through the seaming-roller-operating mechanism; Fig. 9, a vertical section on line 9-9, Fig. 8; Fig. 10, a horizontal section on line 10-10, Fig. 8; Fig. 11, a section through the upper gear-wheel on line 11-11, Fig. 10; and Figs. 12, 13, and 14 show consecutive forms 30 of the joint between can body and head.

The letter *a* represents a can-supporting track flanked at each side by an endless feed-chain *b*. The chains *b* are connected to each other by transverse rods *b'* to constitute an open feed-apron *B*. The rods *b'* extend across track *a* and are adapted to engage and feed the can-bodies *A* placed upon the track. The chains *b* are held against lateral displacement by guides *a'* and pass over an idler *c* and a feed-drum *d*, notched, as at *c'* *d'*, to engage the rods *b'*. The idler *c* is journaled in a suitable support *c'*, while the drum *d* is journaled at *d'* to a bracket *e'*. This bracket extends laterally from a vertically-adjustable table *e*, to which track *a* is connected at *e'* and which forms a continuation thereof.

Intermittent rotatory movement is imparted to drum *d*, and consequently to apron *B* in the following manner: The power-shaft *f* transmits motion by pulley *f'*, belt *f''* running over idlers *f''*, and by pulley *g'* to a vertical work-shaft *g*, journaled in bearings *g''* of the machine-frame *D*. The shaft *g* has a worm *g'*

engaging worm-wheel *d'*, fast on spindle *d*. The spindle *d* is provided with a crank *d''*, connected by link *d'''* to a lever *d''*, turning on pivot *d''*. To this lever is pivoted a spring-influenced pawl *d''''*, engaging a ratchet-wheel *d''''*, fast on drum *d*. By the means described the rotatory movement of shaft *g* is converted into the desired intermittent movement of apron *B*. A detent *d'''''* engaging ratchet-wheel *d''''*, holds the latter against rotation in the reverse direction.

The apron *B* feeds the cans *A*, together with the superposed heads *A'*, successively upon two vertically-movable platforms *h*, arranged, respectively, underneath two sets of seaming-rollers *j* *j'*. Of these the first set *j* is profiled to form a lap-joint between can-body and can-head, while the second set *j'* is profiled to compress the joint into a flat airtight seam. The rollers *j*, as well as the rollers *j'*, are journaled in slides adapted to rotate around the can-body and which are radially movable, so as to be brought into operative engagement therewith. The means for operating the rollers *j* are identical with those for operating the rollers *j'*, so that the same description will apply to both. The shaft *g* carries a long pinion *g'*, meshing into two sets of differential gear-wheels *k* *l*, of which one set is arranged above platform *h* while the other set is arranged above platform *i*. The upper wheel *k* of each set has a smaller number of teeth than the lower wheel *l*, so that it rotates slightly quicker than the latter. The wheel *l* is rotatably supported upon a collar *o'* of a fixed shaft *o*, having a lower chuck *o''*, which is centered above platform *h* or *i* and around which the rollers *j* or *j'* are revolvable. The chuck *o''* is adapted to enter a central depression *A'* of can-head *A'*. The wheel *l* has an upwardly-extending hub *l'*, Fig. 8, and is provided with an interior bushing *l''*. The upper wheel *k* is rotatably supported upon wheel *l* and has a central eye to embrace hub *l'*. At the bottom of wheel *k* is formed an undulating cam-groove *k'*, Figs. 10 and 11, that alternately approaches and recedes from the center of the wheel. The groove *k'* is engaged by a number of cam-rollers *m*, turning on pins *m''*, that pass downwardly through radial slots *l''* of wheel *l* and are connected to radial slides *N*, that carry the seaming-rollers *j* and *j'*, respectively.

The slides N are guided in radial grooves l^4 of a downward extension l^5 of wheel l . Each slide N is composed of an upper section n and a lower section n' , adjustably connected thereto. Within a surface groove of the upper section n is attached by a screw n^2 a countersunk plate n^3 , to which pin m' is riveted. An adjusting-screw n^4 , turning in bearings n^5 , is received by an opening between parts n and n' and engages a thread cut into part n' , while it can rotate freely within the upper part of the opening. Thus by manipulating screw n^4 the lower part n' , which carries the seaming-rollers j or j' , may be moved radially inward or outward to adapt the machine to can-bodies of different diameters. After the section n' has been properly adjusted it is locked in position by clamp-screw n^6 . As has already been stated, the upper wheel k will by pinion g^4 be rotated slightly faster than the lower wheel l . This excess of movement will cause the cam-groove k' to advance slowly over the surface of lower wheel l in addition to the rotary movement common to both wheels. Thus the cam-rollers m will be moved alternately inward and outward to impart the desired radial movement to slides N, and consequently to the seaming-rollers j and j' . In assembling the parts the cam-rollers m are introduced into groove k' through openings k^2 of wheel k . These openings are subsequently partly closed by plates k^3 , that prevent a vertical displacement of the rollers. After the can 35 A has arrived on platform h or i the platform is raised, so that the can-head A' is pressed against chuck o^2 . The means for raising both platforms are identical and are as follows: The worm g^3 of shaft g meshes into a 40 second worm-wheel p , fast on shaft p' , which is intergeared with cam-shaft p^2 by wheels p^3 , p^4 . Upon shaft p^2 are mounted the cams p^5 , each of which is adapted to oscillate a cam-lever p^6 , Fig. 4, fulcrumed to frame D at p^7 . The free ends of levers p^6 are connected by a 45 rod p^8 , upon which are mounted two pairs of links p^9 . The first pair of links p^9 is connected to a movable lower plate p^{10} , upon which is supported by a cushion p^{11} an upper plate p^{12} , having a post p^{13} , that carries platform h . In like manner the second pair of links p^9 is connected to a lower plate p^{10} , supporting by cushion p^{11} an upper plate p^{12} , the post p^{13} of which carries platform i . The 50 platforms h and i are seated within corresponding recesses of table e and will by the means described be simultaneously raised or lowered. When lowered, their surface is flush with the surface of table e , while when 55 raised the platforms extend a distance above the table. In order to guide the platforms during their vertical movement, they are provided with depending pins p^{14} , that engage corresponding openings of table e . To

center the can-body A upon the platforms, 65 there are arranged over apron B a pair of longitudinal guide-rails q , Fig. 6, having diverging ends q' . The rails q are adjustable and should be so set that the distance between them equals the outer diameter of can-body A. Thus the movement of the feed-apron will cause the can-bodies A to be centered in a longitudinal direction between the rails q . Means are also provided to center the can-body in a transverse direction upon 70 the first platform h . These means consist of a gage r , having a V-shaped notch r' and arranged opposite platform h . The gage r is movable at right angles to the movement of apron B, and to accommodate the gage the 75 front rail q is partly broken away. The means for operating the gage r are as follows: To plate p^{10} is attached an extensible arm r^2 , carrying wedge r^3 , Fig. 4, which is alternately raised or lowered by cam p^5 . The wedge r^3 80 engages a roller r^4 , journaled in hangers r^5 , which are attached to gage r and straddle a support r^6 , projecting from table e . When the wedge r^3 is raised, it will force the gage r 85 backward along its support r^6 to center the 90 can-body upon platform h . When the wedge r^3 descends, the gage will be drawn forward by a spring r^7 .

The table e is vertically adjustable to adapt the machine to can-bodies of different 95 heights. The means for setting table e consist of a shaft s , Fig. 3, having handle s' and a pair of worms s^2 . These worms engage wheels s^3 , Fig. 5, fast on spindles s^4 , journaled at their upper ends in bearings s^5 of frame D. 100 The lower threaded ends of spindles s^4 engage tapped eyes e^3 of table e , so that by turning shaft s the table is raised or lowered. Clamp-screws t , extending through slots D' of frame D, lock the table in position after 105 having been properly adjusted.

The operation of the machine will be readily understood. The can-body A, with superposed head A', Fig. 12, will by apron B be fed along track a and table e and will be 110 pushed upon platform h , where it is centered. The platform is now raised to force head A' against chuck o^2 , after which the can and head will be subjected to the action of the seaming-rollers j , that rotate around the can 115 and simultaneously approach the same. After a lap-seam has thus been formed, Fig. 13, the rollers j recede to liberate the can and the platform h is lowered. The can is now by apron B pushed upon the second platform i , 120 where the operation is repeated and the seam is closed, Fig. 14, to complete the operation.

What I claim is—

1. In a can-heading machine, the combination of a recessed table, with a vertically-movable platform seated therein, a chain for feeding a can-body upon the platform, means for raising and lowering the platform, a chuck 125

above the platform, a series of seaming-rollers surrounding the chuck, and means for imparting a simultaneous rotatory and radial movement to said rollers, substantially as specified.

2. In a can-heading machine, the combination of a track with a feed-apron, a vertically-movable platform, a pair of guide-rails having diverging ends, a gage, and means for reciprocating said gage at right angles to the feed-apron, substantially as specified.

3. In a can-heading machine, the combination of a wheel having a cam-groove with a second wheel having radial guides, slides movable therein, seaming-rollers journaled in the slides, cam-rollers connected to the slides means for and engaging the cam-groove, and rotating the wheels at different speeds, substantially as specified.

4. In a can-heading machine, the combination of a shaft having a chuck and a collar, with a lower wheel rotatably supported on the collar and having radial guides, slides engaging said guides, seaming-rollers journaled in the slides, an upper wheel rotatably supported upon the lower wheel and having a cam-groove, cam-rollers connected to the slides and engaging said groove, and means

for rotating the wheels at different speeds, substantially as specified.

5. In a can-heading machine, the combination of a wheel having a radial guide, with a slide engaging the same and composed of an upper section and a lower section, means for radially adjusting the lower section along the upper section, and a seaming-roller journaled to said lower section, substantially as specified.

6. In a can-heading machine, the combination of a track with a feed-apron, a vertically-movable platform, a chuck above the same, a lower gear-wheel rotatable above the platform, radially-movable slides engaging said wheel, seaming-rollers journaled to the slides, an upper gear-wheel having a cam-groove, cam-rollers connected to the slides and engaging said groove, and means for rotating the wheels at different speeds, substantially as specified.

Signed by me at New York city, Manhattan, New York, this 15th day of June, 1904.

JULIUS BRENZINGER.
